United States Patent Office

Des. 227,097
Patented June 5, 1973

227,097

ARCHERY BOW HANDLE

William R. Stewart and Lonnie P. Griggs, Jacksonville,
Tex., assignors to AMF Incorporated, New York, N.Y.

Filed June 1, 1971, Ser. No. 149,092

Term of patent 14 years

Int. Cl. D22—01

U.S. Cl. D22—5

FIG. 3

FIG. 4

FIG. 1 is a side elevational view of an archery bow handle showing our new design;

FIG. 2 is an elevational view of the side opposite that shown in FIG. 1;

FIG. 3 is a rear elevational view;

FIG. 4 is a front perspective view; and

FIG. 5 is an enlarged fragmentary perspective view of a portion of the bow handle shown in FIG. 1.

We claim:

The ornamental design for an archery bow handle, substantially as shown.
